this 13th day of July,

UNITED STATES PATENT OFFICE.

ALBERT R. TREICHEL AND EDWARD J. BROCK, OF ST. LOUIS, MISSOURI.

PACKING APPARATUS.

1,346,616.

Specification of Letters Patent. Patented July 13, 1920.

Application filed January 17, 1920. Serial No. 352,200.

To all whom it may concern:

Be it known that we, ALBERT R. TREICHEL and EDWARD J. BROCK, citizens of the United States, residing in the city of St. Louis and State of Missouri, have invented new and useful Improvements in Packing Apparatus, of which the following is a specification.

This invention relates to packing apparatus such as employed for packing joints of all kinds, such as occur associated with reciprocating stems or spindles rotating shafts, or in expansion joints, valves, etc. The general object of the invention is to produce a simple and effective packing apparatus.

The invention consists in the novel features, and in the general combination of parts to be particularly described hereinafter, all of which contribute to produce a simple and efficient packing apparatus. A preferred embodiment of our invention will be particularly described in the following specification, while the broad scope of our invention will be pointed out in the appended claims.

In the drawing,

Figure 1 is a transverse section through the packing apparatus embodying our invention;

Fig. 2 is a longitudinal section through the packing apparatus;

Fig. 3 is a vertical section taken on the line 3—3 of Fig. 1;

Fig. 4 is a side elevation, partially broken away, illustrating another form or embodiment of the invention;

Fig. 5 is a side elevation of the parts shown in Fig. 4, partially broken away;

Fig. 6 is a plan showing a form of spring which we may employ;

Fig. 7 is a side elevation of the spring shown in Fig. 6;

Fig. 8 is a front elevation of the packing apparatus shown in Fig. 2 with the cover plate removed;

Fig. 9 is a perspective broken away and illustrating the preferred form of the meeting faces for the packing members;

Fig. 10 is a view similar to Fig. 9, but showing another form the meeting faces of the packing-members may take;

Fig. 11 is a vertical section through two packing-members but showing a modified construction in which each packing-member is built up of separate plates; and

Fig. 12 is a fragmentary cross-section

showing another means we may employ for pressing the packing-members toward each other.

Referring more particularly to the parts 60 and especially to Figs. 1 to 3, 1 represents a stuffing-box which is to be employed to pack a packing-member such as a reciprocating stem 2 which may be reciprocated through an opening in a wall 3 to which the stuffing-box 1 is attached. The stuffing-box is of cylindrical form and presents a bore 4 within which we place our packing-members a' and a'' , and b' and b'' .

The packing members are produced by 70 dividing a disk or block into a plurality of sections; in the present instance there are two sections to each disk and we prefer to employ a plurality of these disks so as to increase the effectiveness of the packing and 75 so as to increase the length of the stuffing-box to meet special requirements. In the present instance we have shown only two of these packing disks, but it should be understood that we may employ any number 80 of these disks as may be required. The packing-members a' and a'' have meeting faces which are respectively tongued and grooved, that is to say, one of the faces will have a tongue received in a corresponding 85 groove in the face of the opposite packing-member, for example, see Fig. 3 in which the packing-member a' is represented as having a tongue 5 which is received in a corresponding groove 6 formed in the pack- 90 ing member a'' . In addition to this, the packing-members are not formed by dividing the packing disks on a straight line, but are formed with a jog 7 (see Fig. 1), that is to say, the packing-members are formed 95 with adjacent meeting faces 8 near the member 2 which is to be packed, and with other meeting faces 9 near their periphery which are off-set from the plane of the meeting faces 8. The meeting faces 8 and 9 are connected through the medium of the trans- 100 verse shoulder or jog 7 referred to above.

We provide means for resiliently pressing the packing-members inwardly and toward each other so that they will engage the 105 side of the member which is being packed. This is preferably accomplished by springs arranged in any suitable manner, for example, in Figs. 1 to 3, I have illustrated coil springs 10 disposed respectively around the 110 stems of long screws 11, each screw being received in a pocket 12 drilled in the pack-

ing-member a' and screwing into the lower packing-member a^2 . It will be evident that these springs will pull or press the packing-members toward each other and will yieldingly hold the same against the side of the stem 2.

In order to pack the packing-members on their outer side, they are provided with alining grooves 12^a which coöperate to form

- 10 a continuous annular groove passing around the packing-members. In this annular groove we provide an expansion ring 13 which is preferably in the form of a split ring, which tends to assume a slightly 15 larger diameter than that of the bore 4. In assembling the parts, this spring ring or expansion ring, is slightly compressed so as to force it into the bore of the stuffing-box; once it is in place, it tends to expand and 20 packs the space between the packing-members and the bore of the stuffing-box. Instead of employing coil springs, such as spring 10, we may employ a spring such as spring 14 illustrated in Figs. 4 to 7. In 25 using this form of spring, we simply provide the packing members with inner grooves 15 disposed at the bottoms of the annular grooves 16 which receive the expansion ring 17. In order to apply the 30 spring ring 14, it is simply opened out sufficiently so as to enable it to be passed over the packing-members. Ring 14 may be formed of fine spring wire, the ends being 35 bent so as to form transverse fingers 18 which should be received in pockets in the groove 15 to prevent the spring from working around on the packing members.

- 40 In assembling the parts, the different packing disks which are to be placed within the stuffing-box are assembled so that the meeting faces of one pair of the packing-members is staggered or intermediately disposed with respect to the packing members of the other disk, (see Fig. 8). In order to 45 insure that the packing disks will maintain this relation, we provide the bottom of the stuffing-box with slots 18 which extend in the direction in which members a' and a^2 move in approaching each other, and the 50 member a^2 is provided with small pins 19 which are received respectively in these slots. Similar pins 20 are provided on the outer face of the member b^2 of the packing-members which are received in slots 21 which are formed on the inner face of a 55 cover-plate 22 which is fastened by bolts 23 on the end of the stuffing-box.

- 60 Attention is called to Fig. 9 as illustrating the form of the meeting faces of the packing-members. By reason of the tongue 5 a rabbet groove 24 is formed in the face of the packing-member on each side of the tongue. The use of the tongues 5 and 65 grooves 6 operates to prevent an opening being formed longitudinally of the stuffing-

box and between the packing-members, and this arrangement is particularly advisable in short stuffing-boxes, but in longer stuffing-boxes the form of meeting face shown in Fig. 10 may be employed in which case 70 we rely upon the staggering of the different packing disks to prevent leakage through the packing-members consecutively, parallel with the packed member.

In practice there might be some difficulty 75 in practically forming the tongues 5 and grooves 6 from a solid piece. If desired, this can be avoided by constructing the packing disk of three plates—25, 26 and 27 (see Fig. 11), the plates 25 and 26 being of the same 80 thickness as the rabbet groove 24 shown in Fig. 9 and the middle or intermediate plate 27 being of the same width as the outer groove which receives the expansion ring 28, the tongue 29 corresponding to tongue 5 85 being formed the full width of the plate 27; in other words, in this construction we make the tongue and the ring of the same width.

In Fig. 11, the upper portion of the figure represents a packing-member c' and the lower portion represents a packing member c^2 , each packing member being composed of sections of the plates 25, 26 and 27 and meeting together to form a joint 30. The plates 25, 26 and 27 may be connected together in 90 any suitable manner, for example, by brazing, or by the use of dowel pins; and the packing-members c' and c^2 may be pressed toward each other by means of the springs such as spring 14 or springs such as the 95 spring 10 described above, or by any other suitable means.

We prefer to employ iron or steel for 100 making the packing-members and provide the same with bushings 31 of any suitable bearing material. When these bushings become worn, they can be renewed.

We may provide means such as that shown in Fig. 12 for holding the packing-members against the shaft. In this case we provide a 110 plurality of small leaf springs 32 which lie in the annular space between the divided packing disk 33 and the expansion ring 34; each spring is held in place by a pocket 35 that receives the spring.

What we claim and desire to secure by Letters Patent is:

1. In packing apparatus, the combination of a stuffing-box having a bore and forming an annular packing chamber around the 120 member to be packed, oppositely disposed packing-members received in the packing chamber for engaging opposite sides of the member to be packed, means for resiliently pressing the packing-members toward each 125 other, said packing-members having alining grooves coöoperating to form a continuous annular groove passing around the exterior of the packing-members, and a split expansion ring fitting in the annular groove, ex- 130

eriting its pressure against the bore of the stuffing box and packing the space between the packing-members and the face of said bore.

5 2. In packing apparatus, the combination of a stuffing-box having a bore and forming an annular packing chamber around the member to be packed, oppositely disposed packing-members received in the packing 10 chamber for engaging opposite sides of the member to be packed and having faces lying adjacent to each other, springs for pressing the packing-members toward each other and for holding the same against the side 15 of the member to be packed, said packing-members having alining grooves in the outer surface thereof to form a continuous annular groove passing around the exterior of the packing-members, and a split expansion 20 ring fitting in the annular groove, exerting its pressure against the bore of the stuffing-box and packing the space between the packing-members and the face of said bore.

3. In packing apparatus, the combination 25 of a stuffing-box having a bore and forming an annular packing chamber around the member to be packed, oppositely disposed packing-members received in the packing chamber for engaging opposite sides of the 30 member to be packed and having faces lying adjacent to each other, the face of one packing-member having a tongue, the face of the opposite packing member having a groove receiving the tongue, springs for 35 pressing the packing-members toward each other and for holding the same against the side of the member to be packed, said packing-members having alining grooves in the outer surface thereof to form a continuous 40 annular groove passing around the exterior of the packing-members, and a split expansion ring fitting in the annular groove, exerting its pressure against the bore of the stuffing-box and packing the same between 45 the packing-members and the face of said bore.

4. In packing apparatus, the combination of a stuffing-box having a bore forming an annular packing chamber around the mem-

ber to be packed, a disk divided into a plurality of sections constituting packing-members, said packing-members having bushings of bearing material for engaging opposite sides of the member to be packed, and disposed within the packing chamber, springs 50 for forcing the packing members inwardly against the side of the member to be packed, said packing-members respectively having grooves and coöperating tongues on their meeting faces and having alining grooves in 55 their outer faces coöperating to form a continuous annular groove passing around the exterior of the packing-members, and a split expansion ring fitting in the annular groove exerting its pressure against the bore of the 60 stuffing-box and packing the space between the packing-members and the face of said bore.

5. In packing apparatus, the combination of a stuffing-box, a packing disk received 70 therein formed of side plates and an intermediate plate, said disk being divided into sections constituting packing-members, one of said packing-members having meeting faces with tongues the width of the intermediate plate, the opposite packing-member 75 having grooves of the same width as the intermediate plate, and receiving the tongues.

6. In packing apparatus, the combination of a stuffing-box, a packing disk received 80 therein formed of side plates and an intermediate plate, said disk being divided into sections constituting packing-members, one of said packing members having meeting faces with tongues the width of the intermediate plate, the opposite packing-member 85 having grooves of the same width as the intermediate plate, and receiving the tongues, said packing-members having alining grooves in their outer faces of the same 90 width as the intermediate plate, and an expansion ring received in the grooves for packing the space between the packing members and the wall of the stuffing-box.

In testimony whereof we have hereunto 95 set our hands.

ALBERT R. TREICHEL.
EDWARD J. BROCK.
